UNITED STATES PATENT OFFICE.

EUGENE G. SMITH, OF CHICAGO, ILLINOIS; FRANK Z. SMITH, HARRY T. SMITH, AND MITTIE M. SLAGLE EXECUTORS OF SAID EUGENE G. SMITH, DECEASED.

CAR-AXLE TRANSMISSION.

Application filed February 13, 1924, Serial No. 692,582. Renewed June 24, 1927.

This invention relates to belt drives for driving generators from car axles and more particularly to a universal driving pulley and guide means for guiding the same.

The objects of this invention are to provide an improved driving apparatus for driving generators from car axles; to provide a universal pulley for driving the belt and means for holding the pulley in substantially vertical position; and in general to provide such an improved apparatus as will be described more fully hereinafter.

In the accompanying drawings illustrating this invention;

Figure 1 is a front view of a car truck with my improved driving apparatus mounted thereon;

Figure 2 is a detail plan view showing one end of the guide bar and the bearings therefor;

Figure 3 is a sectional view taken on the line 3—3 of Figure 1;

Figure 4 is a front view showing a modified form of construction;

Figure 5 is a plan view of the form shown in Figure 4; and

Figure 6 is an enlarged detail showing the support and spring at one end of the bar shown in Figures 4 and 5.

While for many years it has been the common practice to use ordinary rigid pulleys on car axles for driving the belts with generators, I have recently introduced universal pulleys for such purpose. It will be understood that the rims of such pulleys are free to oscillate or swing in all directions in a plane at right angles to the axis of the car axle. Consequently it is desirable or essential to provide means for supporting such pulleys so that they will swing in a vertical plane only and not in a horizontal plane, or, in other words, to hold the rim in a substantially vertical position.

In accordance with more or less standard practice, car wheels or axles have a certain amount of lateral movement with respect to the truck frames or with respect to their bearings. The arbitrary limit of this movement in accordance with standard practice is one and one half inches in either direction or in other words a total possible lateral movement of the wheels and axles with respect to the frame, of three inches. It will be readily understood that if guides or guide

wheels were fixed rigidly to the frame for

engagement with the universal pulley, the lateral movement of such pulley would cause it to pound against the guides and furthermore the pulley would be swung or thrown violently from side to side as such movement occurred between the truck frame and the wheels. In order to prevent such pounding, I provide such guiding mechanism as is shown in these drawings. In the particular form shown, the axle 7 is provided with the usual wheels 8 and support the truck frame 9 in the usual manner, the bearings being omitted as they may be of any ordinary or preferred construction and do not form a part of the present invention. The axle 7 is provided with a universal pulley 10 preferably of the character shown in my co-pending application for transmissions for generators, filed March 31, 1923, Serial No. 629,096. This pulley is adapted to swing in a vertical plane under the influence of the belt 11 so that the pulley will always be in alignment with the belt. In order to hold the pulley in substantially vertical position, I provide guide rollers 12 and 13 which are arranged on either side of the rim of the pulley adjacent to the top and are carried by a cross bar or guide bar 14. This bar may be bent or arranged in any suitable manner in order to conform with different body or truck constructions and so as not to strike or interfere with any of the parts thereof. The portions of this bar beyond the parts supporting the rollers may be offset as shown in Figure 1. The bar is preferably made rectangular in cross section and its ends are supported in bearings 15 and 16 which are secured to the side beams 9 in any suitable manner and which may be held by bolts 17. The bearings 15 and 16 have vertically arranged pins or bolts 18 which engage with slots 19 in the ends of the bar 14. The heads of the bolts 18 are preferably countersunk in the lower portions of the bearings and rest on the top of the beams so that they cannot work out of position. The slots 19 are of just sufficient length to permit the proper lateral movement of the guide bar 14, which will ordinarily be about three inches.

A small amount of clearance is left between the sides of the pulley 10 and the guide rollers, preferably of about one-quarter inch, and when the wheels and axles move in one direction with respect to the frame the pulley 10 will be crowded or moved

against the corresponding guide roller and will tend to move the bar 14 longitudinally in such direction. The pins or bolts 18 co-acting with the slots 19 prevent the bar from 5 moving too great a distance and consequently the universal pulley will be held in proper working position. The weight of the cross bar and guide rollers may be made sufficient so that it will require some force 10 to move it longitudinally which will tend to steady the movement of the universal pulley as it moves laterally with respect to the frame. If desired, a certain amount of tension or friction may be provided between 15 the bar and its bearings which may be adjusted or regulated by tightening the bolts 18 if a slight amount of give or yielding is provided in the bearing.

In the modified form of construction 20 shown in Figures 4 to 6, inclusive, the pulley 10 is provided with guide rollers 20 which are mounted on a guide bar 21. This bar is offset or bent as shown at 22 in a horizontal plane in order to clear the wheel 10 25 as shown in Figures 4 and 5. The ends of the bar engage with bearings 23 on the side beams 9 of the truck frame. These bearings are also provided with bolts 24 which engage with slots 25 in the ends of the bar in 30 the manner above described. In this form of the device, I also provide tension means tending to hold the cross bar in a normal or fixed position. In the particular form shown, springs 25 are arranged at each end 35 of the bar. One end of each spring engages with the adjacent face of the bearing 23 and the opposite end engages with a washer or collar 26 which is slidably mounted on the bar 21 and which engages with another collar or washer 27 which is secured to the bar 21 in any suitable manner as by means of a pin or bolt 28. A keeper 29 is secured to the bearing 23 and is adapted to be engaged by the collar 26 to limit the movement 40 thereof.

When the axle and wheel shifts laterally, the wheel 10 will engage with one of the guide rollers 20 and will tend to move the bar 21 in the corresponding direction 45 against the tension of one of the springs 25. When the bar is pressing against one of the springs the spring at the opposite end will be held by its keeper so that it will not oppose the action of the other spring. In 50 this manner the springs tend to hold the guide bar and rollers in normal or fixed position but at the same time permitting a certain amount of lateral movement. It will also be seen that the springs tend to cushion 55 the action between the universal pulley and the guide rollers so that the rollers or pulley will not be apt to be injured by the lateral movement of the wheels and axle.

In view of the fact that there are many 60 types of car trucks it will be apparent that

this invention will of necessity be modified for the different conditions, and therefore I do not wish to be limited to the particular form or arrangement herein shown and described, except as specified in the following 70 claims, in which I claim:

1. A guide for a universal pulley mounted on a car axle, comprising a transverse guide member, guides secured to said member and adapted to engage with the pulley, bearings 75 for said guide member and means limiting the longitudinal movement of such member.

2. A guide mechanism of the character set forth, comprising bearings secured to a car truck, a bar mounted in said bearings, means 80 for limiting the longitudinal movement of the bar and guide rollers mounted on the bar for engagement with the universal pulley.

3. The combination with a railway car, of a universal pulley mounted on one of the axles thereof, bearings secured to the truck frame, a cross bar mounted in said bearings and having slots in the ends thereof, bolts 85 engaging with said slots and guide rollers secured to the bar and adapted to engage with the sides of the pulley.

4. In an apparatus of the character set forth, the combination with a railway car, of a universal pulley mounted on one of the car axles, bearings secured to the side beams 95 of the truck frame, bolts engaging with said bearings, a cross bar having its ends fitting in said bearings and having slots for receiving the bolts, guide members secured to said bar and adapted to engage with the pulley, 100 the arrangement being such that the bar may have a limited movement with respect to the frame, substantially as described.

5. The combination with a railway car, of a universal pulley mounted on one of the car 105 axles, guide means for holding the pulley in vertical position, and resilient means tending to hold the guide means in central or normal position.

6. A guide for a universal pulley of the 110 character set forth, comprising a cross bar, guide members secured to the bar and adapted to engage with the pulley, bearings for said bar and springs tending to hold the bar in normal position.

7. The combination with a railway car, of a universal pulley mounted on one of its axles, bearings secured to the sides of the truck frame, a cross bar slidably mounted in said bearings, guide rollers on said bar for engagement with a pulley and springs co-acting with the bar tending to hold it in central or normal position.

8. In an apparatus of the character set 125 forth, the combination with a car axle, of a universal pulley, bearings secured to the truck frame, a transverse bar slidably mounted in said bearings, collars slidably mounted on said bar, springs interposed between the collars and the bearings, keepers 130

for limiting the movement of the collars and washers secured to the bar and adapted to engage with the collars.

9. The combination with a railway car truck, of bearings mounted on the truck beams, a guide bar slidably mounted in said bearings, a universal pulley mounted on the

car axle, guide rollers for engagement with said pulley, said guide bar being bent to provide clearance for the pulley and means tending to limit the longitudinal movement of said bar.

EUGENE G. SMITH.
